2,157,195

FURNACE AND COMBUSTION CHAMBER

Frank O. Weeks, Portland, Oreg.

Application March 26, 1937, Serial No. 133,250

1 Claim. (Cl. 110—30)

This invention is directed to an improvement in furnaces and more particularly to a combustion chamber for furnaces wherein provision is made for the effective handling of various types of fuel and for the effective burning of unconsumed gases to insure the maximum thermal efficiency of the heat units of the fuel.

The primary object of the present invention is the provision of a furnace of this type wherein the grate is made up of independent relatively inclined sections serving to direct the incoming fuel to the point of maximum incandescence, with the unconsumed gases permitted free escape into the combustion chamber proper, with the further provision of means for selectively admitting within the area of the unconsumed gases one or more jets of air for mingling with and serving for the burning of such gases to increase heat production.

A further object of the invention is the provision of a furnace of this type having independent combustion chambers for the burning of various types of fuel, the unconsumed gases of each of which are delivered within the area of the air jets for efficient consumption of such gases.

A further object of the invention is the provision of means wherein the grate is made up as independent units, the fuel directing elements of which are independently removable to provide for handling various types of fuel.

The invention is illustrated in the accompanying drawings, in which:

Figure 1 is a perspective view of the improved furnace, a single coil only being shown for convenience.

Figure 2 is a section on the line 2—2 of Figure 1.

Figure 3 is a section on the line 3—3 of Figure 1.

Figure 4 is a more or less diagrammatic view showing the relation existing between the air jet pipes.

Figure 5 is a section on the line 5—5 of Figure 1.

Figure 6 is a broken perspective view of one of the grate sections.

Figure 7 is a perspective view of one of the sides of such grate section.

Figure 8 is an enlarged section on the line 8—8 of Figure 6.

Figure 9 is a perspective view of one of the auxiliary grate bars.

Figure 10 is a section on the line 10—10 of Figure 5.

The improved furnace, which aside from the details to be hereinafter specifically noted may be of any desired size or relative proportions, comprises a vertically extending body including side walls which are of substantially L-shape including upright portions 29 and forwardly extending portions 14. A rear wall 28 provided with clean-out doors 30 extends the full height of the furnace, a front wall 15 closing the front included between the forwardly extending portions 14 and a front wall 27 closing the front above the extensions 14.

An upper wall 13 overlies and encloses the upper ends of the extensions 14, an upper wall 31 closing the upper end of the upright portions 29. The upper wall 13 is formed with an opening from which rises a rigid throat section 11 to the upper edge of which is hingedly connected at 12 a hopper 10 of appropriate size to receive and feed the fuel to the furnace.

A plate 42 bridges the space included in the forward portion of the furnace, the plate resting upon rear supports 43 and a forward edge extending inwardly from the front wall 15. The plate 42 is parallel with the top 13 and spaced therefrom an appropriate distance to provide a fire-box. In this fire-box are included two grate sections each, as shown more particularly in Figures 6, 7 and 8, including side walls 44 formed with downwardly inclined slots 45 which open through one vertical edge of the side wall and terminate materially short of the other vertical edge of such wall. The side walls 43 of each section are held in removable unitary formation through cross-rods 47 passing through the side walls at appropriate points and secured by nuts 48 countersunk in the outer surfaces of the side walls, as shown more particularly in Figure 8.

Each grate section includes grate bars in the form of plates 49 slidably cooperating with the side walls 44 through the cooperation of such grate bars with a pair of transversely aligned slots 45. As thus arranged, the grate bars incline downwardly, are held in proper position by gravity and the weight of the fuel, and yet may be readily removed when desired.

The grate proper is made up of two such grate sections with their edges 53 in contact, such edges 53 being those edges remote from the lower ends of the grate bars. When thus positioned, the grate proper constitutes two grate sections, the grate bars of each inclined downwardly toward each other with a considerable space between the proximate ends of the grate bars.

The front plate 15 is formed in its upper por-

tion in alignment with the combustion chamber having the grate bars with a door 16 having the usual draft inlet 17, the space below the plate 42 being also open through the plate 15 controlled by a door 20 with the usual draft door 21. The space controlled by the door 20 constitutes another fuel chamber, the bottom being constituted by the bottom 22 of the furnace on which is arranged a lining 24 formed with longitudinal depressions 26 providing fuel supporting ridges 25.

In the combustion space is arranged a coil indicated at 36, the inlet to which is through a pipe 40 and controlled by a valve 39 and the outlets from which are shown at 41. As illustrated more particularly in Figure 3, the coil formation within the furnace is in the shape of a header 38 to which one, two or more coils 36 may be connected. Of course, the coil formation proper is not a particularly important feature of the invention except possibly in its location, and it is contemplated that any type of coil or any number of coils may be employed, as desired. The coils may be supported on supports 37 provided within the furnace and, of course, the coils may be of a form more particularly desired for the type of heat, that is hot water, steam or the like, or in the event it is designed more particularly for the production of hot air as the external heating medium, the coils may be entirely eliminated.

Air jet pipes 55 lead through the front wall 15 below the plate 42, being preferably passed through the support 43 and turned upwardly with nozzle outlets at 57 directing the air transverse of and in rear of the grate section. Air inlet pipes 56 lead from the sides of the furnace, terminating in nozzles 58 above and substantially in line with the nozzles 57. The ends of the air pipes 55 and 56 beyond the furnace walls are provided with an air inlet casting 63 having air inlets 64 and providing a casing for a valve 61 controlled by a hand wheel 62 by which admission of air through the particular pipe may be governed.

The escaping products of combustion are led through a flue 33 opening through the top plate 31 and leading to a chimney 32, the pipe having the usual damper 34 and check 35.

The furnace may be provided with a clean-out door 36 and with a covering 65 of asbestos or other non-heat conducting material. The usual chains 18 may be connected to the doors 17 by means of a lug 19 on the door for the control of the air admission in the usual manner.

In the use of some fuel, there may be found a tendency to clog between the grate bars, under which circumstances an auxiliary bar or bars 50 may be employed, which are provided at one end with a depending projection 51 and in spaced relation to such projection with short legs 52 through the medium of which projection and legs the auxiliary bar may be engaged over any grate bar and extend into the space between the proximate ends of the grate bars to break up the fuel as it descends. These auxiliary bars may be solid, as shown in Figure 6, or of skeleton form, as indicated in Figure 9.

The fuel is introduced into the hopper 10 and fed by gravity to the grate bars. This fuel is gradually moved downwardly toward the lower end which, of course, is the point of maximum incandescence. The partially consumed gases

escape between the grate bars into the combustion space, air being admitted through the opening of the door 17 and jets of air being introduced through the pipes 55 and 56 to mingle forcibly with the unconsumed gases and cause their combustion. The heat at this point is, of course, the maximum and is utilized for heating the water in the coils or the air in the combustion area if the furnace is to be used for the production of hot air. Through the control of the air inlet to the pipes 55 and 56, as well as the opening of the draft door 17, the furnace may be regulated to insure almost complete combustion of the unconsumed gases, whereby the thermal efficiency of the furnace is at the maximum and little if any unconsumed products of combustion escape through the flue.

If the fuel is of an exceedingly fine character with a resultant tendency to clogging, the auxiliary grate bars 50 may be employed with any grade bar, though preferably used with the lowermost one, to effectively break up such clogging tendency. If the fuel is unusually coarse, one or more of the grate bars may be removed to facilitate the feeding and burning of the fuel.

The finer fuel is indicated at 60 in Figure 5, and if for any reason it is desired to utilize wood, such may be introduced through the door 20 and placed on the ridges 25 and ignited. In this use, of course, the air jets may or may not be used, though obviously they are of aid in consuming the unburned gases from the wood-fuel.

It is to be noted that the air is introduced substantially at the point where the unconsumed gases pass between the grate bars toward the combustion space. This insures the most effective combustion of the unconsumed gases and the development at this area of the maximum heat efficiency.

That the coils shown in Figs. 3 and 5 may be of any desired size and number and are installed in one, two or more units as desired and so placed in relation to the combustion chamber so as to utilize the maximum amount of heat.

In Fig. 6; 64 is a plate inserted in slot formed by groove 65 and ridge 66 for the purpose of confining the combustion of the fuel in the grates to any desired place. Plate 64 may be any desired number or width so as to close the opening between two or more of the grates as may be desired or determined.

What is claimed to be new is:

A grate bar construction for furnaces including plates arranged in pairs, the plates of one pair being formed with downwardly inclined channels extending from one edge of each plate but terminating short of the opposite edge of such plate, the plates of the other pair being formed with upwardly inclined channels opening through similar edges of each plate of the pair and terminating short of the opposite edges of the plates, grate bars cooperating with aligned slots of each pair of plates, the plates being arranged with their non-channelled edges in contact to provide a completely uninterrupted fuel-receiving space between the relatively adjacent edges of the inclined plates, and auxiliary grate bars removably secured to any of the first mentioned grate bars to provide projecting elements beyond that edge of such grate bar defining the fuel space.

FRANK O. WEEKS.
